UNITED STATES PATENT OFFICE

HERMANN DEILE, OF BERLIN-LICHTENBERG, GERMANY, ASSIGNOR TO ACETA G. M. B. H.,
OF BERLIN-LICHTENBERG, GERMANY, A CORPORATION OF GERMANY

TWISTING CONTINUOUSLY SPUN ARTIFICIAL THREADS

Application filed March 6, 1930, Serial No. 433,695, and in Germany March 28, 1929.

My present invention relates to an improvement in twisting artificial silk threads.

In most of the hitherto known twisting systems, especially in the case of operating 5 with artificial silk threads, twisting is started with a yarn already wound up on a reel or a bobbin. The end of the thread or of the bundle of threads to be twisted is, for instance, fixed on the winding spool by passing it several times around the latter, while the apparatus is at rest; then the thread is subsequently guided through the different running off mechanism (draught rollers, thread-guides, eyelets, travellers, etc.); finally, the twisting spindle, the winding-on 10 and running off mechanism are put into operation.

When spinning and twisting artificial threads simultaneously, the application of 20 these methods will, however, not be possible, since the spinning operation does not permit any discontinuity or interruption. Since the winding-on devices of all of the known mechanisms can take up only a limited 25 length of thread it is necessary that a device, when full, may be replaced by a fresh device so that twisting may proceed without disturbance of the spinning process. This can be done in known manner with a spinneret 30 operating with low speeds of draught (40 to 60 meters per minute) as generally used in wet centrifugal spinning processes by rinsing the end of the thread by means of a liquid through the funnel-like thread-guide 35 into the spinning pot. In view of the very high speeds of draught (150 to 200 meters per minute) in dry-spinning processes, however, and in view of the extremely small weight per unit length of thread spun by 40 the dry-spinning method, complicated devices are in most cases necessary for the same purpose; for instance, in box spinning according to a dry spinning process it is necessary to use a current of compressed air.

45 According to my invention, it becomes possible to start easily with the usual twisting systems the twisting of a thread delivered at a high speed or to interchange the collecting devices after having taken up the desired 50 quantity of twisted yarn without loss of

fibers. For this purpose, use is made of an auxiliary thread of sufficient strength and length, and of a fineness corresponding with the titre of the threads to be twisted in each case. This auxiliary thread is doubled, and 55 its ends are introduced into the twisting machine while the loop of the thread, is held firmly with the fingers of one hand. The twisting machine is set into operation whereby the doubled thread immediately becomes 60 twisted. Meanwhile, the artificial thread is issued by the spinning device and wound on a lap roller or running to a collecting device, 65 is drawn into a loop which is then passed through the loop of the auxiliary thread. The loop of the auxiliary thread is then released by which manipulation the main 70 thread is attached to it and shortly afterwards is drawn into the winding device. At the same time the length of the artificial 75 thread between the auxiliary thread and the lap spool or the collecting device is broken. The artificial thread is held securely by the closed loop of the auxiliary thread, and is guided by the latter onto the winding-on device. This terminates the operation which 80 allows to start the twisting of the thread issued from the spinneret or to guide the thread from a collecting device already full to a new one without interruption of the spinning process.

In the annexed drawings there are illustrated by way of example some modes of executing my invention with various twisting systems.

Figs. 1 and 2 illustrate the application of my invention in box twisting, Fig. 3 in ring twisting and Fig. 4 in flyer twisting of artificial threads. Figs. 5 and 6 show the same principle applied in interchanging the collecting devices in a ring twisting machine; however, it may be used in an analogous manner in other twisting machines.

Referring to Fig. 1, *a* designates the thread issued from the spinning nozzle. It passes 85 around a roller *c* and is at first wound on the lap roller *b*. In order to introduce the thread into the centrifugal twisting machine, the ends of the doubled auxiliary thread *d* are introduced through the funnel *h* into the cen- 90

trifuge *g* against the wall of which they are held by centrifugal force of the running machine. At the same time, the doubled thread *d*, the loop *e* of which is held with the fingers of one hand, is twisted. Now, through this loop *e* is passed (see Fig. 2) a loop *f* drawn carefully from the main thread *a* and at the beginning also held with a finger at *f*. The loop *e* is then released, whereupon it closes and holds the loop *f* of the main thread; the loop *f* is also released, and the main thread is detached from the lap roller *b*, and is drawn by the auxiliary thread *d* into the box *g*. The twisting of the artificial thread is thus commenced.

Fig. 3 shows the application of the same process in ring twisting. The doubled auxiliary thread *d* is secured to the winding-on spool *i*, and passed through the traveller *m* and the thread guide *n*. The loop *e* is held with two fingers and the spindle *k* is set in motion, whereby the doubled thread is twisted. A loop of the main thread *a* is drawn at *f* and passed through the loop *e* of the auxiliary thread, the further procedure being the same as that described above.

Fig. 4 illustrates the application of the same process in flyer twisting. In this case also the doubled auxiliary thread *d* is first secured to the winding-on device *i*, thereupon passed through the eyelets of the flyer *q* and held at its loop *e*. The flyer spindle *p* is set in motion and the loop *f* of the main thread is passed through the loop *e*, the further operations being the same as those already described.

In Figs. 5 and 6 *i*₁ designates a full spool and *i*₂ the empty spool to which is to be transferred the thread *a* issuing from the spinning apparatus. In the ring twisting apparatus, illustrated by way of example, several spindles *k* are arranged in a row, the thread is caused to reciprocate vertically in known manner during the twisting operation by means of the ring rail *s*, and wound on by means of the traveller *m* which moves in the ring *l*. *e* is the draught roller and *n* the thread guide, around which, during the twisting operation, the balloon of the yarn is formed.

When the spool *i*₁ is full, the doubled auxiliary thread *d* is wound on the adjacent empty spool *i*₂, passed through the traveller *m* and the eyelet *n*. The loop *u* of the auxiliary thread *d* is held between two fingers of the right hand; the spindle *k* is then set in rotation whereby the double thread *d* is twisted. At the same time, with the third finger of the right hand, the loop *v* is drawn out from the main thread *a* and passed through the loop *u*, the main thread is cut by scissors *t* and the loop *u* is released which immediately closes. The free end of the main thread *a* is securely held by the auxiliary thread and guided on the empty spool.

In this way the thread is transferred from the full spool to the adjacent empty spool without interruption of the spinning process. In the case of spinning at several places at the same time, there being a spinning place, between each pair of adjacent twisting devices, the threads can be transferred in the same manner from a collecting device either to the device on its right or to that on its left, provided that the number of twisting devices exceeds by one the number of the corresponding spinning places. Instead of a ring twisting device any other of the known twisting devices may be used.

What I claim is:—

In a process of twisting a continuously spun artificial thread the steps which comprise doubling an auxiliary thread to form a loop, introducing the both ends of the auxiliary thread into the twisting device, pulling out a loop from the main thread to be twisted, setting the twisting device in operation to twist the auxiliary thread, and passing the loop of the main thread through the loop of the auxiliary thread.

In testimony whereof, I affix my signature.

HERMANN DEILE.
